FIG. 1.

FIG. 2.

INVENTOR:

Georges Aurelien Chaillley
Emile Meunier
ATTY.

UNITED STATES PATENT OFFICE.

GEORGES AURÉLIEN CHAILLIEY, OF LYON ST. CLAIR CALUIRE, FRANCE.

MAGNETO WITH WATER-TIGHT CASING.

1,336,196.

Specification of Letters Patent.

Patented Apr. 6, 1920.

Application filed March 6, 1918. Serial No. 220,731.

To all whom it may concern:

Be it known that I, GEORGES AURÉLIEN CHAILLIEY, a citizen of the Republic of France, residing at Chemin du Vallon, Lyon 5 St. Clair Caluire, Rhone, in the Republic of France, have invented new and useful Improvements in Magnetos with Water-Tight Casings, of which the following is a specification.

10 The object of the present invention is a magneto of special construction, it being specially designed to afford an absolutely watertight apparatus.

This result is obtained by the special arrangement of its cylindrical field frame which carries pole pieces cast together with the same. The different orifices in this field frame (oil holes, screws for contact disks) are covered by suitable rings. The invention 20 is clearly set forth in the accompanying drawing, which represents an example of the invention, and relates to a method of practical execution of the same, showing the advantages and the special features.

25 Figure 1 is a longitudinal section of the magneto designed according to the invention.

Fig. 2 is a cross section of the same.

The present magneto comprises a cylindrical field frame 4 (Figs. 1 and 2) which carries the pole pieces 1 and 2 (Fig. 2), cast together with the same, also a magnet 3 (Figs. 1 and 2) this being a portion of a cylinder, and an end cap 5 (Fig. 1) having 30 two bores, one adapted to receive the ball bearing ring 6 and the other to receive the cam ring, 7.

On the collector side, the field frame is threaded internally at the same diameter as 40 the field bore, in order to receive the support 8 of the ball-bearing 9. Three holes are provided in this support in order to bring the lubricating oil to the ball-bearing surface. A boss 19 on the top of the frame 45 opposite the collector serves to receive the high tension brush holder 10.

The lower base 11 of non-magnetic material serves to attach the magneto as may be desired either upon a flat base or a round 50 base, using in the latter case the surfaces A and B.

The contact break used with these magnetos is reversible, and to provide for running the magneto in one direction or the 55 other, all that is required is to shift by the

required angle the single or double cam ring 7 and this is carried out by the use of the outer ring 12 which is connected to the cam ring 7 by screws 13 and 14 passing through transverse slots provided in the cap 5. The 60 object of the ring 12 is to entirely cover said transverse slots. The screws 13 and 14 are also used to set the rings in either of these two positions.

The milled ring 15 which is provided with 65 an opening can be given a slight rotation in order to uncover the single oil hole 5^a which is used for lubricating the two bearings 6 and 9. An oblique hole 22 in the cap 5 brings the oil to the bearing 6, and a 70 groove 16 is made obliquely in the frame in order to avoid the boss 19 and to facilitate the flow of oil, and this groove is covered by the magnet. This latter arrangement serves to bring the oil to the bearing 9 on 75 the collector side.

The magnet fits upon the field frame without the use of any attaching screws, and it is held in a fixed position between the flanges of the frame and the end cap 5. 80

A tight passage is also secured for the shaft 17 by the use of a small felt-covered disk 21 which presses upon this shaft and the inner ball-bearing ring.

It will be observed that the present design 85 allows of machine work in standard types in a very practical manner as all the parts are entirely lathe-turned.

It is understood that the present design 90 is not intended to limit the possible arrangements, and that while remaining within the limits of the invention, all necessary special modifications may be made either as regards details or the proportions, of the entire apparatus.

Having now described my invention, what 95 I claim as new and desire to secure by Letters Patent is:

1. An ignition magneto containing, in combination, a cylindrical field frame provided with a flange and having a threaded bore on one side and a cylindrical portion on the other, a ball bearing mounted in the threaded bore of said frame, a cap with two bores mounted on the cylindrical portion 100 of the frame, a ball-bearing disposed in one of the bores of the cap, a contact break disk mounted in the other bore of the cap, a cylindrical magnet fitted on the field frame 105 of the frame, a ball-bearing disposed in one of the bores of the cap, a contact break disk mounted in the other bore of the cap, a cylindrical magnet fitted on the field frame between the flange and the cap, and a lower 110

base with cylindrical sides and flat bottom attached to said magnet, substantially as described and for the purpose set forth.

2. An ignition magneto containing, in combination a cylindrical field frame provided with a flange and having a threaded bore on one side and a cylindrical portion on the other, a ball bearing mounted in the threaded bore of said frame, a cap with two bores mounted on the cylindrical portion of the frame and having transverse slots, a ball-bearing disposed in one of the bores of the cap, a contact break disk mounted in the other bore of said cap, an outer ring 10 rounding the cap, screws connecting said outer ring to the contact break disk and extending through the said transverse slots, a cylindrical magnet fitted on the field frame between the flange and the cap, and a lower base with cylindrical sides and flat bottom 15 attached to said magnet, substantially as described and for the purpose set forth.
3. An ignition magneto containing, in combination, a cylindrical field frame provided on the outside with a flange and having a threaded bore on one side and a cylindrical portion on the other, a ball bearing mounted in the threaded bore of said frame, a cap with two bores mounted 20 on the cylindrical portion of the frame, a ball bearing disposed in one of the bores of the cap, a contact disk mounted in the other bore of said cap, the field frame being provided in its outer surface with a spiral 25 groove extending to the first mentioned ball bearing and the cap being provided with a conduit extending to the other ball bearing and with an oil hole in communication with the spiral groove on the field frame and with 30 the said conduit, an angularly adjustable ring provided with an opening and adapted 35

to cover the said oil hole, a cylindrical magnet fitted on the field frame between the flange and the cap, and a lower base with cylindrical sides and flat bottom attached 45 to said magnet, substantially as described and for the purpose set forth.

4. An ignition magneto comprising in combination: a cylindrical non magnetic frame having a peripheral flange, pole 50 pieces securely held in said cylindrical frame, a cap secured to one end of the frame and a segmental cylindrical magnet fitting over the frame and pole pieces and clamped between the said peripheral flange and the 55 cap.

5. An ignition magneto comprising in combination: a cylindrical non magnetic frame having a peripheral flange, pole 60 pieces securely held in said cylindrical frame, a cap secured to one end of the frame, a segmental cylindrical magnet fitting over the frame and pole pieces and a base, the magnet and the base being clamped between the said peripheral flange and the cap. 65

6. An ignition magneto comprising in combination: a cylindrical non magnetic frame having a peripheral flange, pole pieces securely held in said cylindrical frame, a cap secured to one end of the frame, 70 a segmental cylindrical magnet fitting over the frame and pole pieces and a base having a flat bottom and cylindrical side faces, the magnet and the base being clamped between the said peripheral flange and the cap. 75

In testimony whereof I have signed my name to this specification in the presence of two subscribing witnesses.

GEORGES AURÉLIEN CHAILLEY.
